UNITED STATES PATENT OFFICE.

BRYAN S. WAKEMAN, OF BATAVIA, ASSIGNOR OF ELEVEN-TWENTIETHS
TO SAMPSON E. TUCKER, OF ALBANY, NEW YORK.

CAN-OPENER.

SPECIFICATION forming part of Letters Patent No. 338,211, dated March 16, 1886.

Application filed November 23, 1885. Serial No. 183,705. (No model.)

To all whom it may concern:

Be it known that I, BRYAN S. WAKEMAN, of the town of Batavia, county of Genesee, and State of New York, have invented a new 5 and useful Improvement in Can-Openers, of which the following is a specification.

My invention relates to that class of devices known as "can-openers," and its object is to produce and offer to the public a manufactured 10 article that will furnish the most economical and expeditious means of opening sheet-metal cans.

Accompanying and forming a part of this specification is one plate of drawings containing 15 four figures illustrating my invention, in all of which like letters refer to corresponding parts.

Figure 1 is a perspective of my improved can-opener. Fig. 2 is a longitudinal sectional 20 view of the same. Fig. 3 is a view of the cutter and thumb-nut. Fig. 4 is a transverse sectional view of the shank and cutter, taken on the line *x x*.

Referring to the drawings, *H* is the handle, 25 and *B* the shank, of the can-opener. *S* is a longitudinal slot in said shank.

K is a hook projecting forwardly from the end of the shank *B*, its plane being lower than that of the lower surface of the shank *B*.

M M are grooves or channels, broken by 30 the slot *S* in the under surface of the shank.

C is the cutter, composed of the threaded haft *a* and the triangular blade *a'*, the edges *a²* and *a³* being beveled on both sides.

D is the thumb-nut, working on the threaded haft *a* of the cutter *C*.

To construct my improved can-opener, the handle *H*, shank *B*, and hook *K* are usually cast in one piece, as being the simpler and 40 cheaper method; but of course they can be constructed separately and of different materials, and joined together. The cutter *C*, being entirely separate, is joined to the shank *B* by passing the haft *a* up through the slot *S*, and then adjusting to it the thumb-nut *D*. Of course, when the latter is turned sufficiently 45 to bring it to bear on the upper surface of the shank *B*, by tightening the pressure of the

thumb-nut, the upper edge, *a⁴*, of the cutter-blade *a'* is drawn firmly against the under surface of the said shank and into one of the grooves or channels *M M*, the latter serving to hold the cutter firmly in place, and to prevent it from either turning or from being moved from that point of the shank. 50

In using this improved can-opener the pointed hook *K* is first pushed through the sheet metal at about the center of the top of the can. The thumb-nut *D* being loosened, the cutter *C* is moved along the slot *S* until it reaches a point on the shank *B* suitable to the size of the cut to be made, when the thumb-nut is tightened and the cutter firmly fixed in position by the edge *a⁴* being held in one of the grooves or channels *M M*. Then, by pushing down on the handle, the hook *K*, through being on a lower plane than the upper surface of the shank *B*, serving as a fulcrum without again puncturing the sheet metal, the triangular blade *a'* is forced through the sheet 60 metal, and by moving the can-opener around upon the hook *K* as a pivot a complete circular opening is cut in the sheet metal. The edges *a²* and *a³* of the cutter-blade are beveled on both sides, the effect of which in cutting is 65 to turn down both edges of the sheet metal and do away with any sharp outwardly-projecting edges. 70

Having thus described my invention, what I claim, and desire to secure by Letters Patent, is—

In a can-opener, the combination of the cutter *C* and thumb-nut *D* with the handle *H* and shank *B*, said shank being provided with the forwardly-projecting hook *K*, the longitudinal slot *S*, and the grooves or channels *M M*, the latter to prevent the cutter from slipping from any point of the said shank at which it may be set, constructed and operated substantially as hereinbefore set forth. 85

In witness whereof I have hereunto set my hand this 19th day of November, 1885.

BRYAN S. WAKEMAN.

In presence of—

GEO. R. WILSON,
F. W. BOOTH.
